(57) **CLAIM**

The ornamental design for a resistance band, as shown and described.

DESCRIPTION

FIG. 1 is a perspective view of a resistance band showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the resistance band where the resistance band is in a configuration of use; and,

FIG. 9 is an enlarged view of portion 9 shown in FIG. 1. The resistance band is shown with a symbolic break in its length and the appearance of any portion of the resistance band between the break lines form no part of the claimed design.
